CLAIM

The ornamental design for a projector lamp unit for vehicle, as shown and described.

DESCRIPTION

FIG. 1. is a front perspective view of the front, right, and top sides of a projector lamp unit for vehicle showing our new design;

FIG. 2. is a front view thereof;

FIG. 3. is a rear view thereof;

FIG. 4. is a left side view thereof;

FIG. 5. is a right side view thereof;

FIG. 6. is a top plan view thereof; and,

FIG. 7. is a bottom plan view thereof.

The broken lines shown illustrate portions of the projector lamp unit for vehicle in which the design is embodied and form no part of the claimed design.

1 Claim, 7 Drawing Sheets
